CLAIM

We claim the ornamental design for a power receptacle, as shown and described.

DESCRIPTION

FIG. 1 is a front, upper perspective view of a power receptacle showing our new design;

FIG. 2 is a front, lower perspective view of the power receptacle of FIG. 1;

FIG. 3 is a rear, upper perspective view of the power receptacle of FIG. 1;

FIG. 4 is a front elevation view of the power receptacle of FIG. 1;

FIG. 5 is a rear elevation view of the power receptacle of FIG. 1;

FIG. 6 is a left side elevation view of the power receptacle of FIG. 1;

FIG. 7 is a right side elevation view of the power receptacle of FIG. 1;

FIG. 8 is a top plan view of the power receptacle of FIG. 1;

FIG. 9 is a bottom plan view of the power receptacle of FIG. 1;

FIG. 10 is a front, upper perspective view of another example of the power receptacle;

FIG. 11 is a front, lower perspective view of the power receptacle of FIG. 10;

FIG. 12 is a rear, upper perspective view of the power receptacle of FIG. 10;

FIG. 13 is a front elevation view of the power receptacle of FIG. 10;

(Continued)

FIG. 14 is a rear elevation view of the power receptacle of FIG. 10;
 FIG. 15 is a left side elevation view of the power receptacle of FIG. 10;
 FIG. 16 is a right side elevation view of the power receptacle of FIG. 10;
 FIG. 17 is a top plan view of the power receptacle of FIG. 10;
 FIG. 18 is a bottom plan view of the power receptacle of FIG. 10;
 FIG. 19 is a front, upper perspective view of a further example of the power receptacle;
 FIG. 20 is a front, lower perspective view of the power receptacle of FIG. 19;
 FIG. 21 is a rear, upper perspective view of the power receptacle of FIG. 19;
 FIG. 22 is a front elevation view of the power receptacle of FIG. 19;
 FIG. 23 is a rear elevation view of the power receptacle of FIG. 19;
 FIG. 24 is a left side elevation view of the power receptacle of FIG. 19;
 FIG. 25 is a right side elevation view of the power receptacle of FIG. 19;
 FIG. 26 is a top plan view of the power receptacle of FIG. 19; and,
 FIG. 27 is a bottom plan view of the power receptacle of FIG. 19.
 In the drawings, the broken lines depict portions of the article that form no part of the claimed design. The flexible power cord of the power receptacle is also shown with break lines illustrated to indicate a symbolic break in the respective length of the design thereof. The appearance of any portion of the article between the break lines forms no part of the claimed design.
